CLAIM

The ornamental design for an intake manifold for an engine, as shown and described.

DESCRIPTION

FIG. 1 is an elevated rear-right perspective view of an intake manifold for an engine according to the new design; FIG. 2 is an elevated rear-left perspective view thereof; FIG. 3 is an elevated front-left perspective view thereof; FIG. 4 is an elevated front-right perspective view thereof; FIG. 5 is a rear elevational view thereof; FIG. 6 is a front elevational view thereof; FIG. 7 is a right-side elevational view thereof; FIG. 8 is a left-side elevational view thereof; FIG. 9 is a top plan view thereof; and, FIG. 10 is a bottom plan view thereof.

All broken lines shown in the drawings are for environmental purposes only and form no part of the claimed design.

1 Claim, 8 Drawing Sheets
